NAVIGATING TABLE

Bo Klas Oskar Lundberg, Linkoping, Sweden

Application September 21, 1933, Serial No. 690,382
In Sweden April 25, 1932

4 Claims. (Cl. 33—76)

The present invention relates to improvements in navigating tables for air-craft and ships, provided with a mapholder with map or sea chart, and a rule, limb, or the like, its particular object being so to design the apparatus that a pilot or a helmsman may carry out the geometric problems necessary for navigation by position fixing or the like, such as marking courses and bearings, angles of drift or the like, by using one hand only.

It is necessary for this purpose that the rule or the like used for the marking may be exactly held in the required position on the table, and that it be released and moved to a new position and fixed there again, by a simple manipulation. Provisions for such purpose are known, but they present as a rule the disadvantage that they darken a large part of the underlying map or the like, and they are very often considerably complicated, whereby the various operations cannot be carried out with the required ease and security.

The object of the present invention is to remove the said disadvantages, and the invention is characterized in that a frame is located on the table between the side pieces of which the map, the sea chart or the like, or a portion of these, is placed, and which thus will not darken any portion of the map etc.

The invention is further characterized in that the table is yieldingly or resiliently mounted relatively to the frame so that the rule or the like inserted under two sides of the frame may be clamped between the table and said sides, and be released and moved only when actuated by the hand. Further, means are provided to hold the table firmly in a depressed position relative to the frame to facilitate the manipulation and exact adjustment of the rule, for releasing the table from the said stopping position and for returning the same to the clamping position. Thus, a pressure impulse is used in order to release and clamp the rule, which impulse must be the most natural and comfortable which the hand grasping the rule is able to exert.

An embodiment of the invention is illustrated in the accompanying drawings in which:

Figure 1 is the navigating table viewed from above with the rule clamped,

Figure 2 is a longitudinal section, and

Figure 3 a cross section of the same.

Figure 4 is a modified detail.

Figures 5-8 show the stopping device in lateral view, partly sectioned, in four different positions, and

Figure 9 shows the same viewed from above in the position illustrated in Figure 6.

The table proper 1 consists of a plane disc, and constitutes a support for a roll map or the like running over the rounded edges 2, and rolled up on rollers 3. The rounded edges may be replaced by rollers 4 (Figure 4), to reduce the friction. On the table is disposed a rectangular frame 5 which, by means of bolts 6 running through the table one in each corner, is secured to a bottom 7 which may be fixed to the aircraft or the ship. The frame 5 is provided on its underside with a layer of rubber or some other material having a great coefficient of friction. The bolts 6 between the table and the bottom 7 carry springs 8 which press the table against the frame. On the underside of the table is located a wall 10, and on the bottom 7 a wall 9, which walls are so arranged relatively to each other that the stopping device, indicated by the triangle 11 in Figure 2, 20 may be placed between them. The rule 12, which is preferably transparent, is provided with a handle for easy manipulation, said handle being stationary or slidable along the rule, and clamped between two side pieces of the frame in the position shown in Figure 1.

The stopping device consists of a main catch 15 and an auxiliary catch 17, which are mounted each on its own bolt 16, 18 secured to the wall 10 connected to the table. The catches, each under 30 the action of its own spring (not shown), tend to move in a counterclockwise direction (Figure 5). The main catch has an upper stop face 19, a lower notch 20, and a projection 21. The auxiliary catch is provided with a stop face 22. Bolts 35 13, 14 are located on the wall 9.

The apparatus operates in the following manner. When the rule 12 is in the clamped position, and thus the table has been moved with respect to the frame 5 the stopping device assumes the position shown in Figure 5. When the table is depressed the main catch 15 actuated by the spring is turned so that the stop face 19 comes under the bolt 13 on the wall 9 of the frame, as illustrated in Figure 6. Thus the table 45 is stopped in this intermediate position, and the released rule may now be moved at pleasure. Upon the further depression of the table the projection 21 strikes against the bolt 14, and thus the main catch is turned so that its stop face 19 50 is brought out of contact with the bolt 13, and its notch 20 engages the stop face 22 of the spring-actuated auxiliary catch 17. The table has now reached its bottom position (Figure 7), and, when the pressure on the same ceases, is returned to 55

the clamping position by the springs 8. The notch 20 maintains during said procedure its engagement with the stop face 22, and thus holds the catch 15 out of the stopping position until the stop face 19 has cleared the bolt 13, whereupon the two catches are freed from each other by the catch 17 striking against the bolt 14 (see Figure 8).

Of course the same effect is obtained if the two catches are connected with the frame, and the two bolts cooperating with the catches are connected with the table.

Having now described my invention, what I claim as new and desire to secure by Letters Patent is:

1. In a navigating instrument, a vertically movable table carrying a chart, a frame superimposed on said table and surrounding at least a portion of the chart to be observed, a rule clamped between said frame and table, spring means for raising said table towards said frame, a stopping mechanism responsive to lowering of said table to a certain extent with respect to said frame for arresting said table in a lowered position, and means responsive to further lowering of said table for disabling said stopping mechanism and permitting said spring means to return said table into the clamping position.

2. An instrument in accordance with claim 1, in which said stopping mechanism consists of a spring actuated main catch connected with said table and having a stop face, a stop mounted on said frame and cooperating with said stop face to arrest said table in a lowered position, a second stop on said frame, a projection on said catch cooperating with said second stop to release said stop face from the first mentioned stop, and an auxiliary spring actuated catch cooperating with said main catch under the control of said second stop to hold said stop face out of the range of the first mentioned stop.

3. In a navigating instrument of the character described, a table for a chart, a frame superimposed upon said table and surrounding at least a portion of the chart to be observed, a resilient connection between said frame and table, and a rule clamped between said table and frame.

4. In a navigating instrument of the character described, a table for a chart carrying a superimposed frame surrounding at least a portion of the chart to be observed, spring means for pressing said table against said frame, and a rule clamped between said table and frame.
